SKI TOWING APPARATUS

Moise Paquette, Ste. Agathe des Monts, Quebec,
Canada

Application October 13, 1938, Serial No. 234,837

6 Claims. (Cl. 104—178)

The present invention relates to towing apparatus and more particularly to apparatus for towing or pulling skiers up-hill.

An object of the invention is the provision of 5 towing apparatus of generally improved design.

Another object of the invention is to provide towing apparatus of the above character which is relatively inexpensive in construction.

A further object of the invention is to provide 10 towing apparatus of the above character which can be erected and operated at a comparatively low cost.

Still another object of the invention is to provide 15 towing mechanism of the aforesaid character which is efficient and reliable in operation.

Other objects and advantages of the invention will become apparent as the description progresses.

In the accompanying drawing forming a part 20 of this specification and in which like reference characters are employed to designate corresponding parts throughout the same:

Figure 1 is a side elevational view showing the 25 apparatus in assembled arrangement for towing skiers up a hill,

Figure 2 is a fragmentary top plan view showing the lower portion of the apparatus,

Figure 3 is a similar view of the upper portion of the apparatus,

Figure 4 is a side elevational view of the same,

Figure 5 is a perspective view of the drive mechanism, and

Figure 6 is a rear end view of the same.

Referring to the drawing, wherein for the purpose 30 of illustration is shown a preferred embodiment of the invention, the upper portion of the apparatus, that is, that portion at the top of a hill embodies an upstanding support standard 10 in the form of a vertically anchored post

rigidly braced by an inclined brace bar 11. To 35 an eye 12 on the post 10 is connected one end of a block and tackle mechanism 13, of the conventional chain hoist type, disposed so that its opposite end connects with an eye on the end of a U-shaped pulley bracket 14 which rotatably

supports a grooved pulley 15. To the outward 40 extension of the pulley bracket 14 is connected a depending rod 16 provided with a weight 17 on the lower suspended end and adapted to maintain the pulley 15 in an approximately vertical plane.

Over the pulley 15 is trained the upper end loop 45 of a continuous towing rope 18.

At the lower end of the apparatus, that is at the foot of the hill or slide, is mounted rope drive mechanism which may constitute a striped

automobile chassis and particularly such as has outlived its usefulness as a vehicle. The chassis frame, indicated at F, is horizontally supported upon posts 20 anchored in the ground. On the outer or rear end of the frame is mounted a 5 shaft 21, in the form of a solid axle, having grooved pulley wheels 22 and 23 fixed on the ends and arranged in a vertical plane. On the intermediate portion of the shaft 21 is secured a drive gear 24 in mesh with a pinion 25 fixed 10 on a drive shaft 26. The drive shaft 26 may correspond to the vehicle propeller shaft and connects with the engine generally indicated at E through the usual transmission and clutch mechanism. On the chassis frame F, adjacent the pulleys 22 and 23, are rotatably mounted a pair of idler pulleys 27 and 28 arranged in a plane inclined from the horizontal, as shown at Figures 15 and 6, and having an auxiliary loop of the tow-rope, indicated at L, trained thereover. This 20 arrangement enables the training of the tow-rope so that the take-off portion or reach, indicated at T, is driven from the top of the drive pulley 23 while the opposite return reach, indicated at R, comes onto the bottom of the opposite complementary drive pulley 22.

This formation of the drive mechanism acts to effectively space the opposite sections or reaches of the tow-rope vertically and laterally, the upper towing reach being arranged uppermost, as 30 shown at Figure 1. The bottom return portion or reach of the rope is guided on vertically arranged pulleys 30 journaled on gudgeons mounted in the upper portion of a plurality of spaced posts 31.

This apparatus provides efficient means for 35 towing or pulling skiers up a hill inclination on or adjacent to a skiing slide. Its relatively simple construction and the provision of means for utilising a relatively inexpensive power unit enables erection and operation at a comparatively low cost. The block and tackle mechanism connecting the upper pulley with its supporting post also enables adjustment so that the rope may be made suitably taut while in use and loosened when the apparatus is inoperative.

It is to be understood that the form of my invention herein shown and described is to be taken as a preferred example of the same, and that various changes as to the shape, size and arrangement 40 of parts may be resorted to without departing from the spirit of the invention or the scope of the subjoined claims.

Having thus described my invention, I claim:

1. In apparatus for towing skiers up an in-

- clination, a pulley adapted to be supported at an upper part of the inclination, a pair of transversely spaced drive pulleys secured on a common drive shaft at a lower position of the inclination, 5 a pair of idler pulleys angularly supported adjacent the drive pulleys, an endless rope trained over the upper pulley, the drive and idler pulleys so as to horizontally space the reaches of the towing apparatus, and means for rotating the said 10 drive shaft and pulleys.
2. In apparatus for towing skiers up an inclination, a support member at an elevated position on the inclination, a pulley attached to the said support member, an endless rope trained over the 15 said pulley, a drive shaft mounted horizontally at a lower elevation of the inclination, a pair of drive pulleys fixed on the drive shaft in spaced positions, a pair of idler pulleys rotatably mounted adjacent the drive pulleys, the said idler pulleys 20 being disposed so that the endless rope may be trained in such manner that the towing reach will take-off from the top of one drive pulley while the return reach will engage the opposite drive pulley at the bottom thereof, and means for rotating 25 the drive shaft.
3. In apparatus for towing skiers up an inclination, a support member at an elevated position on the inclination, a pulley attached to the said support member, an endless rope trained 30 over the said pulley, a drive shaft mounted horizontally at a lower elevation of the inclination, a pair of drive pulleys fixed on the drive shaft in spaced positions, a pair of idler pulleys rotatably mounted adjacent the drive pulleys, the said 35 idler pulleys being disposed so that the endless rope may be trained in such manner that the towing reach will take-off from the top of one drive pulley while the return reach will engage the opposite drive pulley at the bottom thereof, 40 means for rotating the drive shaft, and means for adjusting the tension of the endless rope.
4. In apparatus for towing skiers up an inclination, a support standard disposed at an elevated position relative to the inclination, a vertically arranged pulley attached to the said standard, a horizontally arranged shaft rotatably supported in a downward position relative to the 45 inclination, a pair of vertically disposed drive pulleys fixed on the drive shaft at transversely spaced positions, a pair of inclined idler pulleys rotatably mounted adjacent the drive pulleys, an endless rope trained over the upper and lower pulleys and idler pulleys and arranged so that the upwardly moving towing reach will take-off from the top of one drive pulley while the return reach is trained to initially engage the bottom of the opposite drive pulley, and motor operated mechanism for rotating the said drive shaft. 1
5. In apparatus for towing skiers up an inclination, a support standard mounted at an elevated position relative to the inclination, a pulley connected with the said standard; a drive mechanism mounted at a downward position relative to the said support standard including a drive shaft mounted horizontally on a support, a pair of drive pulleys fixed on the drive shaft in spaced positions, a gear secured on the intermediate portion of the drive shaft, a pinion in mesh with the 2 said gear, a propeller shaft secured to the pinion and operable by a source of power to rotate the drive pulleys; a pair of idler pulleys rotatably mounted adjacent the drive pulleys, and an endless rope trained over the upper, drive and idler 2 pulleys in such manner that the opposite reaches of the rope will assume horizontally spaced positions. 2
6. In apparatus for towing skiers up an inclination, a support standard mounted at an elevated 3 position relative to the inclination, a pulley connected with the said standard; a drive mechanism mounted at a downward position relative to the said support standard including a drive shaft mounted horizontally on a support, a pair of drive 3 pulleys fixed on the drive shaft in spaced positions, a gear secured on the intermediate portion of the drive shaft, a pinion in mesh with the 3 said gear, a propeller shaft integral with the pinion and operable by a source of power to rotate 4 the drive pulleys; a pair of idler pulleys rotatably mounted adjacent the drive pulleys, and endless rope trained over the upper, drive and idler 4 pulleys in such manner that the opposite reaches of the rope will assume horizontally spaced positions, and means for regulating the tension of the said endless rope. 4

MOISE PAQUETTE.
